UNITED STATES PATENT OFFICE.

EDWARD E. PINKERTON, OF CHICAGO, ILLINOIS.

FOLDING RECEPTACLE.

1,243,626.

Specification of Letters Patent. Patented Oct. 16, 1917.

Application filed June 5, 1915. Serial No. 32,314.

To all whom it may concern:

Be it known that I, EDWARD E. PINKERTON, a citizen of the United States, and a resident of the city of Chicago, county of 5 Cook, and State of Illinois, have invented certain new and useful Improvements in Folding Receptacles, of which the following is a specification.

My invention relates to improvements in 10 folding receptacles, and has for its object the provision of a simple and efficient construction of this character which is capable of economical manufacture.

The invention consists in the combinations 15 and arrangements of parts hereinafter described and claimed.

The invention will be best understood by reference to the accompanying drawings forming a part of this specification, and in 20 which,

Figure 1 is a perspective view of a receptacle embodying my invention and shown in closed position,

Fig. 2, a perspective view of the receptacle shown at one stage in the folding thereof,

Fig. 3, a plan view of the complete receptacle shown spread out flat,

Fig. 4, a section taken on line 4—4 of 30 Fig. 3, and

Fig. 5, a plan view of the blank from which the receptacle is made.

The preferred form of construction, as illustrated in the drawings comprises a 35 main side piece 6 having a cover flap 7 arranged at one end and foldable thereon, said cover flap 7 being provided with a securing flap 8 adapted to be inserted in the end of the receptacle to lock all parts in closed position, as indicated in Fig. 1. Main side piece 6 is provided at one edge with a securing flap 9 which is inserted in a side of the receptacle under cover flap 7 to secure this part of the receptacle against opening. At 40 the other side of main side piece 6 is arranged a flap 10 and a flap 11 is arranged at the free edge of flap 10. Flaps 12 and 13 are arranged at the ends of flaps 10 and 11, as shown in Fig. 5, said flaps 12 and 13 being provided with slits and openings 14 and 15 and glued lines 16, as indicated. Flaps 12 and 13 are also provided with glued securing flaps 17 and 18 which are adapted to fold over the ends of flaps 10 and 11 to secure flaps 12 and 13 thereto. The slits and 55 openings 14 and 15, coupled with the glued

lines 16, form a series of pockets on the faces of flaps 10 and 11 for the reception of hairpins or similar small articles.

In use, the articles are inserted in the 60 pockets formed by slits and openings 14 and 15, then flap 11 is folded on top of flap 10 and both folded on top of main side piece 6, the flap 9 being folded over flap 10, as indicated in Fig. 2. Then flap 7 is folded over 65 flaps 9 and 10 and the securing flap 8 inserted in the end of the package, as indicated in Fig. 1, thus completing the receptacle.

While I have illustrated and described the 70 preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I 80 claim as new and desire to secure by Letters Patent is:

1. A folding receptacle formed from a single blank and comprising a main receptacle side; a cover side at the end of said 85 main side and foldable thereon; a securing flap at the free edge of said cover side; a side flap at one side of said main side and foldable thereon in a direction substantially at right angles to the direction of fold of said 90 cover side; a second side flap on the free edge of said first mentioned side flap and foldable thereon; and a securing flap at the other side of said main side, substantially as described. 95

2. A folding receptacle formed from a single blank and comprising a main receptacle side; a cover side at the end of said main side and foldable thereon; a securing flap at the free edge of said cover side; a 100 side flap at one side of said main side and foldable thereon in a direction substantially at right angles to the direction of fold of said cover side; a second side flap on the free edge of said first mentioned side flap and foldable thereon; retaining pockets on the inner faces of said side flaps; and a securing flap at the other side of said main side, substantially as described. 105

3. A folding receptacle formed from a 110 single blank and comprising a main receptacle side; a cover side at the end of said

main side and foldable thereon; a securing flap at the end of said cover side; a side flap at one side of said main side and foldable thereon in a direction substantially at right angles to the direction of fold of said cover side; a second side flap on the free edge of said first mentioned side flap and foldable thereon; flaps at the ends of said side flaps corresponding to said cover side and folded onto said side flaps, there being a plurality of openings in said folded flaps and said folded flaps being secured to said

side flaps adjacent adjoining sides of said openings to form pockets; and a securing flap at the other side of said main side, substantially as described.

In testimony whereof I have signed my name to this specification in the presence of two subscribing witnesses.

EDWARD E. PINKERTON.
